US0D1067969S

(12) **United States Design Patent** (10) **Patent No.:** **US D1,067,969 S**
(45) **Date of Patent:** **** Mar. 25, 2025**

(54) **PRINTER**

(71) Applicant: **Yan Sun**, Anhui (CN)

(72) Inventor: **Yan Sun**, Anhui (CN)

(**) Term: **15 Years**

(21) Appl. No.: **29/978,984**

(22) Filed: **Dec. 17, 2024**

(51) **LOC (15) Cl.** **18-99**

(52) **U.S. Cl.**

USPC **D18/19**

(58) **Field of Classification Search**

USPC D18/14, 16, 19, 36, 40, 50, 53, 54, 55,

(57) **CLAIM**

The ornamental design for a printer, as shown and described.

DESCRIPTION

FIG. 1 is a perspective view of a printer showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the printer that form no part of the claimed design.

1 Claim, 8 Drawing Sheets
